Primary Examiner — Cathy Anne MacCormac*(74) Attorney, Agent, or Firm* — Beyer Law Group LLP(57) CLAIM

We claim the ornamental design for the pet toy, as shown and described.

DESCRIPTION

FIG. 1 is a perspective view of a pet toy in accordance with the present design;

FIG. 2 is a front elevational view thereof;

FIG. 3 is a back elevational view thereof;

FIG. 4 is a top plan view thereof;

FIG. 5 is a bottom plan side view thereof;

FIG. 6 is a right side elevational view thereof; and,

FIG. 7 is a left side elevational view thereof.

Features shown in broken lines depict environmental subject matter, are for illustration only and form no part of the claimed design.
